UNITED STATES PATENT OFFICE

160,793

UTILITY LIGHT

Cornelius J. La Roe, New York, N. Y.

Application December 8, 1949, Serial No. 6,505

Term of patent 7 years

(Cl. D48—20)

To all whom it may concern:

Be it known that I, Cornelius J. La Roe, a citizen of the United States, residing at New York city, in the county of New York and State of New York, have invented a new, original, and ornamental Design for a Utility Light, of which the following is a specification, reference being had to the accompanying drawing, forming part hereof.

In the drawing:

Fig. 1 is a front elevation view of a utility light, showing my new design,

Fig. 2 is a top plan view thereof, and

Fig. 3 is a bottom view.

I claim:

The ornamental design for a utility light, as shown.

CORNELIUS J. LA ROE.
